UNITED STATES PATENT OFFICE.

JACOB FRUEH, OF CHICAGO, ILLINOIS.

SIPHON.

No. 910,054.

Specification of Letters Patent.

Patented Jan. 19, 1909.

Application filed April 13, 1908. Serial No. 426,826.

To all whom it may concern:

Be it known that I, JACOB FRUEH, a citizen of the United States, residing at Chicago, in the county of Cook and State of Illinois, have invented certain new and useful Improvements in Siphons; and I do hereby declare the following to be a full, clear, and exact description of the same, reference being had to the accompanying drawings, forming a part of this specification, and to the figures and letters of reference marked thereon.

This invention relates to siphons such as are designed particularly for drawing liquids from casks or barrels into bottles or other small receptacles, and the objects of the invention are to provide a simple, convenient apparatus with which the flow of liquid may be started without the use of the user's mouth and lungs, and with which the flow of liquid may not only be controlled, but stopped at will, or automatically stopped when the smaller vessel is sufficiently filled and the liquid in either instance being retained in the siphon ready to again inaugurate a flow when desired.

Generally speaking, the invention embodies a siphon having a pump in which the pump valves are automatically opened and held open after the flow of liquid has been inaugurated by the operation of the pump, and in addition, when so desired, an automatic stop-valve controlled manually to arrest the flow of liquid at any time, or automatically by a float operated by the liquid in the vessel being filled, and also having means whereby the stop valve may be opened manually when the flow of liquid is to be again inaugurated.

Referring to the accompanying drawings: Figure 1 is a section in a vertical plane through the pump and liquid controlling mechanism of a siphon embodying the present improvements. Fig. 2 is a similar view taken in a vertical plane at right angles to the plane of Fig. 1. Figs. 3 and 4 are detail views of the lever for manually controlling the stop valve. Fig. 5 is a transverse section on the line 5—5, of Fig. 1, and Fig. 6 is a similar section on the line 6—6, of Fig. 1.

Like letters of reference indicate the same parts in all the figures.

The mechanism forming the subject-mat-

ter of the present invention is preferably located in proximity to or forms a part of the discharge end of a flexible siphon tube A, it being understood that said tube A is passed through the bung hole or aperture in the top of a storage barrel or cask, and the discharge end of the siphon located at a point below the liquid level in the barrel or cask.

In the apparatus illustrated, a pump cylinder B is provided, and within the same is a piston C, mounted on the end of a tubular piston rod C'. The upper end of the rod is in communication with and forms an extension of the flexible siphon tube A. The piston is provided with a packing e, preferably adapted to be expanded by setting up its confining heads in the usual manner, and the liquid passing through the hollow piston rod discharges into the pump cylinder through side passages e', Fig. 1, communicating with a transverse passage e² in a bridge piece e³ carrying a gravitating valve D for closing the outlet to the passage and checking the reverse flow of liquid or air through the passage and siphon tube. The valve stem d of the valve D extends through the bottom of the piston and projects a sufficient distance to effect the elevation or opening of the valve when the piston is at the bottom of the cylinder, and consequently when in this position, a free opening is established for the flow of liquid through the siphon tube and piston. Upward movement of the piston allows the valve to close and creates a vacuum below the piston, as in an ordinary pump. In the bottom head E of the cylinder is an upwardly closing check valve F, normally held to its seat by a spiral spring f, but having a central stem f' with which the stem of the piston valve is adapted to contact when the piston is in its lowermost position, whereby both valves will be opened.

With the arrangement thus far described, the operator by grasping the cylinder in one hand and the piston rod in the other hand, and reciprocating the piston or the cylinder with relation to the piston a few times, may draw the liquid into and through the siphon tube, then by pushing the piston to the bottom of the cylinder both valves will be opened, leaving a free passage for the continued flow or siphoning of the liquid. In the preferred arrangement, and in order to

retain the piston at the bottom of the cylinder, a yielding retainer is provided. The retainer shown is in the form of a spring catch G secured to the piston and projecting through an opening g in the upper piston head. At its upper end is a shoulder or incline g' adapted to pass within the cylinder head to resist the upward movement of the piston, but the shoulder is of such form as to yield and permit the movement of the parts upon the application of a pressure greater than would be exerted by the liquid tending to elevate the piston. If so desired, however, the shoulder may be inclined sufficiently to require the attendant to release the catch before the piston can be operated.

The mechanism for stopping the flow of liquid through the siphon is preferably located below the pump mechanism proper, and in the particular embodiment illustrated is contained within a cylindrical prolongation of the cylinder in the form of a detachable housing H. This housing H is provided with side passages h communicating at the upper ends with the lower end of the cylinder and at their lower ends opening into a central valve chamber h', the upper part of the latter in turn communicating with other side passages h² opening or communicating at their lower ends with the passage below the housing. A very light stop valve I is located in the valve chamber h', being guided by the removable head i and a downwardly extending boss i'. The valve is adapted to close against its seat I' by an upward movement in the direction of the flow of the liquid passing through the housing from the siphon tube and pump, whereby the movement of the liquid tends to close the valve. This stop valve is provided with a flexibly connected downwardly extending stem k carrying at its lower end a small float K, normally adapted, by reason of its weight, to hold the valve in its open position, but should said float be lifted, as by the rising of the liquid level in vessel in which the float is placed, the stop valve will be lifted, closed, and by the pressure of the liquid itself kept in its closed position, even though the discharge end of the siphon be lifted out of the liquid receiver.

The float itself is conveniently located in a tubular prolongation L, having bottom and side discharge openings for the liquid, the means whereby the stop valve may be manually controlled being located above the tubular extension. This means for manually controlling the stop valve embodies a bifurcated arm M, projecting into an annular housing N, located between the housing H and the tubular extension L and in position to embrace the valve stem between the stops m. The arm M is adjustably mounted on a transverse shaft M', journaled in a

projection n on the housing N, and is adapted to either elevate and close the said valve, to hold it in an intermediate position, or to depress and hold the valve open.

To operate the arm and valve manually, the outer end of the shaft is provided with a spring or transversely yielding operating arm O, having a thumb-piece o at the end against which the operator's thumb or finger may be pressed. At a point in proximity to the end of the yielding arm there is located a retainer therefor embodying two recesses R and R', in which the arm will rest for supporting the valve either in its closed or intermediate position, and a bottom shoulder R² against which the arm may be pressed by the attendant for positively holding the valve open. Between the recess R' and the bottom stop R², is an incline R³, against which the end of the arm rides and by which, owing to the transverse resiliency of the arm, the latter will be moved back into the recess R', whenever released by the attendant, thus insuring the retention or support of the valve normally in its intermediate position. When the operating arm is moved into the recess R, however, it will retain its position therein, thereby holding the valve closed with a positive pressure and preventing the flow of liquid until the valve is again opened, even though the float be lifted out of the liquid in the receiving vessel and elevated above the liquid level of the storage barrel or cask.

To insure the prompt discharge of any liquid below the stop valve after the latter has closed, a small air vent S is formed in the housing below the stop valve, preferably in the head of the housing, and in close proximity to the tubular extension, in order that any liquid which may find its way through said vent will travel down on the outside of the tubular extension into the receptacle being filled.

In the practical operation of the device, the attendant grasps the cylinder and housing in one hand, depresses the stop valve operating arm to its full extent, and gives the piston a sufficient number of reciprocations to start the flow of liquid. The piston is left in its lowermost position and the operating arm of the stop valve is permitted to return to its intermediate position. The flow of liquid will continue until the float rises, or if it be desired to interrupt the flow at any time, the operating arm of the stop valve may be elevated to its upper notch, thereby closing the valve. Assuming that the float has operated to close the stop valve and the attendant desires to shift the discharge end into another receptacle or to lift the same above the liquid level in the cask, the operating arm of the stop valve is moved to the upper notch so as to insure

- the holding of the valve closed, then in order to start the flow of liquid it is simply necessary to lower the discharge end and depress the operating arm so as to open the valve.
- 5 When the operating arm is released the valve moves back to its normal intermediate position.

The main object in employing the retainer for holding the piston in its lowermost position, with the pump valves open, is to prevent the lifting of the piston under the pressure and impact of the liquid when the stop valve is suddenly closed, and hence in devices having no stop valve or automatic

10 means for shutting off the flow of liquid the retainer for holding the piston in its lowermost position may be omitted.

Inasmuch as it is preferred to employ a stop valve which will, when closed, be held 20 in its closed position by the pressure of the liquid, it may here be remarked that with this construction it is important that the valve should normally stand just a sufficient distance from its seat to prevent a normal 25 flow of liquid from picking the same up and closing it until the valve is slightly lifted by the float, when the closing action should be quick and entirely automatic. It is for this reason that the operating arm for the stop 30 valve is provided with a means for holding it in its intermediate position to form a support which will permit the valve to close automatically.

Having thus described the invention, what 35 is claimed, is:

1. In a siphon, the combination with a pump cylinder and piston, of valves in the cylinder and piston respectively, and means controlled by the movement of the piston 40 with relation to the cylinder for holding said valves open after the flow of liquid has been inaugurated.

2. In a siphon, the combination with the pump cylinder and piston working therein, 45 of oppositely opening valves mounted in the piston and cylinder respectively and coöperating valve stems projecting in position to open the valves when the piston is at one extreme of its movement.

50 3. In a siphon, the combination with the pump cylinder, the piston mounted therein and the hollow piston rod forming an extension of the siphon tube, of valves located in the piston and cylinder respectively, and 55 valve stems adapted to coöperate in holding the valves open when the piston is at one extreme of its movement.

4. In a siphon, the combination with the pump cylinder, the piston mounted therein 60 and hollow piston rod forming a continuation of the siphon tube, of a valve in the piston opening in the direction of the flow of liquid through the cylinder, a valve in the cylinder also opening in the direction of the

flow of liquid through the cylinder, and 65 means whereby both of said valves are held open when the piston is at one extreme of its movement.

5. The combination of the following instrumentalities arranged in consecutive order and having a single axis to form a siphon starter and controlling mechanism, to wit, a pump having a piston and cylinder, a stop valve closing in the direction of the flow of liquid through the siphon and a float for 75 inaugurating the movement of the valve toward its closed position.

6. In a siphon, the combination with the pump for inaugurating the flow of liquid through the siphon and having a cylindrical 80 barrel, a stop valve housing both arranged in axial alinement with the pump barrel, and a tubular extension from said housing, of a stop valve located within the housing and adapted to close in the direction of the 85 flow of liquid through the siphon, a float located within the tubular extension and connected with the stop valve, and means whereby the stop valve may be opened against the pressure of the liquid. 90

7. In a siphon, the combination with the pump cylinder, piston mounted therein and valves mounted in the piston and cylinder respectively, of a stop valve housing connected with and forming an extension in 95 alinement with the cylinder, a tubular extension in alinement with said cylinder and said housing, a stop valve within the housing, and a float controlling said valve located in the tubular extension, substantially 100 as described.

8. In a siphon, the combination with the pump embodying a cylinder, a piston, and valves with means whereby said valves are held in their open position when the piston 105 is at one extreme of its movement, of a stop valve housing, a stop valve located within said housing and adapted to close in the direction of the flow of liquid through the siphon, a float connected with said stop valve, 110 and means for opening said valve against the pressure of liquid tending to hold the same closed.

9. In a siphon, the combination with the pump for inaugurating the flow of liquid 115 through the siphon, a stop valve and a float for moving said valve toward its closed position, of an operating arm for said valve, and a retainer for holding said operating arm with the valve in its closed position and 120 for holding said operating arm with the valve supported in an intermediate position and free to close, substantially as described.

10. In a siphon, the combination with means for inaugurating the flow of liquid 125 through the siphon, a float controlled stop valve for arresting the flow of liquid through the siphon, and an operating arm

for the stop valve, of a retainer for said operating arm embodying notches for holding the valve closed and for supporting the valve in an intermediate position, and an incline and spring for returning the operating arm to its intermediate position when the same has been moved to hold the valve open.

11. In a siphon, the combination with the pump for inaugurating the flow of liquid through the siphon, a stop valve housing having side passages opening in opposite directions and communicating through a central valve chamber, a valve in said chamber adapted to close in the direction of liquid flowing through the siphon, and a float located below and in alinement with the pump and housing and connected with said valve

for moving the same toward its closed position.

12. In a siphon, the combination with the pump embodying a cylinder and a hollow piston rod forming part of the siphon tube, of a piston mounted on said rod and having side passages communicating with each other through a bridge piece and the upwardly opening valve mounted on said bridge piece for checking the reverse flow of liquid through the piston and rod, substantially as described.
